UNITED STATES PATENT OFFICE.

WILLIAM T. MAXWELL, OF PITTSBURGH, PENNSYLVANIA, ASSIGNOR OF SEVEN-SIXTEENTHS TO JOHN GASS, OF PITTSBURGH, PENNSYLVANIA.

WARNING MEANS FOR GRADE CROSSINGS.

Application filed September 6, 1924. Serial No. 736,298.

To all whom it may concern:

Be it known that I, WILLIAM T. MAXWELL, a citizen of the United States, and a resident of Pittsburgh, in the county of Allegheny and State of Pennsylvania, have invented a new and useful Improvement in Warning Means for Grade Crossings, of which the following is a specification.

This invention relates to signals, and particularly to a signaling apparatus for use in indicating to the driver of a vehicle over a highway that a railroad crossing or other dangerous zone is being approached.

The object of the invention is to inform or warn the operator of a vehicle of the proximity of a danger zone in the road ahead, such as railroad crossings, so that it may be approached with caution, the warning being imparted in such manner as to affect the faculties of hearing, seeing and feeling.

It is a special object to provide a construction of the character referred to which is simple, strong and durable, which will not easily get out of order, and which can be readily installed at a nominal cost.

It is a special object to provide as a part of the warning means an apparatus which will initially give a plurality of successive distinctive audible signals, such signals being automatically produced by the passage of the wheels of the vehicle without requiring any special effort or attention on the part of the driver, which audible signals will be properly followed by the setting up of a series of distinctive rapid vibrations of the vehicle, and which in turn will be followed by a visual indication directly in the road bed itself so that it is practically impossible of escaping the attention of the driver and of such character as to make the average driver fearful of crossing the portion of the road bed immediately in advance at a high speed.

These and other objects of the invention will more fully appear when taken in conjunction with the following description and the appended claims.

In the accompanying drawings, Fig. 1 is a diagrammatic plan view showing a portion of a highway including a railroad crossing, and with the invention installed in connection therewith; Fig. 2 a schematic view in section taken longitudinally of the road bed, and illustrating the various parts

shown in Fig. 1; Fig. 3 a plan view showing the construction of one of the audible signaling apparatus employed; Fig. 4 a fragmentary vertical section taken substantially on the lines IV—IV of Figs. 3, 13 and 16; Fig. 5 an enlarged fragmentary plan view illustrating the means employed for locking the extremities of the resounding plates to their supporting members; Fig. 6 a fragmentary detailed view, taken substantially on the line VI—VI of Fig. 3; Fig. 7 a fragmentary detailed view taken substantially on the line VII—VII of Fig. 3; Fig. 8 a fragmentary detailed view illustrating a modified form of the connecting means for anchoring the resounding plates to their supports; Fig. 9 a view similar to Fig. 3 illustrating another embodiment of the audible signaling apparatus; Fig. 10 a detailed view, in plan, illustrating the means for loosely anchoring the resounding plates of Fig. 9 to their supports; Fig. 11 a transverse vertical section taken through the embodiment shown in Fig. 9; Fig. 12 an enlarged detailed view showing the cooperation with one of the specially constructed locking bolts for anchoring the resounding plates in position; Fig. 13 a view similar to Fig. 9 illustrating still another modified embodiment of the audible signaling apparatus; Fig. 14 a transverse vertical section taken substantially on the line XIV—XIV of Fig. 13; Fig. 15 a fragmentary view taken substantially on the line XV—XV of Fig. 13; Fig. 16 a view similar to Fig. 13 illustrating a form of the audible signaling apparatus which may be used for narrow highways; Fig. 17 a detailed view of a blank from which the T-member employed in connection with the resounding plates may be formed; Fig. 18 the form of T-member constructed from the blank illustrated in Fig. 17; Fig. 19 a fragmentary plan view of a still further modification of the invention; Fig. 20 a vertical sectional view taken on line XX—XX of Fig. 19; and Fig. 21 a sectional view taken on the line XXI—XXI of Fig. 20.

The road-bed of a highway or street is indicated in the drawings generally at 1, which is crossed by the railroad tracks 2 indicative of a danger zone. At a convenient distance from either side of the tracks 2 is located an automatically operating apparatus 3 for producing an audible signal or warning to

the drivers of vehicles approaching the tracks from either direction. Interposed between the apparatus 3 and the tracks 2, at both sides thereof, are a plurality of 5 spaced corrugations 4. The corrugations 4 are preferably spaced approximately six feet apart and may consist of small gauge rails, such as indicated in the drawings, embedded in the road-bed with the heads of the rails 10 projecting slightly thereabove. It is to be understood, however, that these corrugations may be made in many different ways, and that the employment of the rails is intended merely as illustrative of one embodiment. 15 Interposed between the corrugations 4 and the tracks, and at a suitable distance from both the corrugations and the tracks, is a specially formed portion 5 in the road-bed, serving as a visual signal or warning instrumentation. Preferably, the portion 5 consists of a special configuration in the road-bed itself in the nature of a depression of 20 substantial width and considerable depth which extends completely across the full width of the roadway, as clearly shown in Fig. 1. The depression 5 may extend either parallel with the tracks 2, as shown in the full lines in said figure, or at any angle thereto as indicated by the dotted lines 5'. 25 The depression 5 or 5', being formed directly in and as a part of the road-bed is clearly and necessarily apparent to the driver of the vehicle, and is purposely fashioned in such dimensions as to naturally cause the 30 average normal driver to considerably reduce his speed upon approaching the crossing 2 at a high speed. It is contemplated placing the portion 5 approximately one hundred feet from the corrugations 4 and at 35 about forty feet from the tracks 2. Applicant however does not limit the invention to any special distances since the contour of the roadway in the region of the crossings may require considerable variations from 40 the distances named. Instead of forming the portions 5 and 5' as a depression, the surface of the road-bed may be raised at 45 these points in the manner indicated by the dotted lines at 6 in Fig. 2. Whether formed 50 as a depression or as a raised portion, the dimensions are such as to cause a driver to slacken his speed when approaching the crossing at a high rate.

Not only does the portion 5 or 5' extend 55 the full width of the roadway, but this is also true of the portions forming the audible signaling apparatus 3 and the transversely extending corrugations 4, these parts in every instance extending substantially the 60 full width of the roadway, so that they must necessarily be traversed by vehicles traveling the highway in either direction, and regardless of their position between the sides of the road.

65 The detailed structure of the apparatus

comprising the audible signal 3 is shown in Figs. 3 to 7 of the drawings. This apparatus comprises a pair of spaced supports extending transversely of the roadway, and preferably consists of a pair of rails 8, 8' 70 embedded in the body of the road-bed with the heads of the rails extending slightly above the upper surface of the road-bed. Mounted and resting directly upon the heads of the rails are a pair of similarly constructed resounding metal plates 9 and 9', the plate 9 extending from one side of the roadway and terminating at its central point, while the plate 9' likewise extends from the opposite side of the roadway to its central 75 point.

The plates 9 and 9' at their ends adjacent the sides of the roadway are provided with struck up tongues 10, 10' which are adapted to extend below and partially embrace the 80 heads of the rails at the extremities thereof. For this purpose, the ends of the rails have the web and base portion cut away leaving merely an extension 11 formed by the head of the rail, in the manner clearly indicated 85 in Figs. 5 and 6 of the drawings. Each of the outer corners of the two plates 9 and 9' are formed in this manner, with the tongues 10 and 10' thereof extending in opposite 90 directions so that the positioning of the tongues between the rails 8 and 8' will serve as a means to limit bodily movement of the plate longitudinally of the roadway.

With the construction described, it is apparent that the tongues 10 and 10' may be 100 shaped in the manner shown in Fig. 3 of the drawings prior to the placing of the plates in operative position upon the rail, it being merely necessary to place the plates upon the rail with the tongues lying slightly 105 beyond the ends 11 thereof, and then move the plates so as to permit the extensions 11 to extend within the space between the ends of the tongues and the body of the plates, and sliding the plates towards each other so 110 as to abut at the central portion of the roadway.

In order to permit free movement of the plates with respect to their supporting rails, the tongues 10 and 10' are so disposed as to 115 permit both a slight movement of the plates from one rail towards the other, and to allow a substantial rise and fall of the plates upon the rails, for a purpose to be subsequently described, and in order to enhance the movement of the plates due to the passage of vehicles thereover, the plates are of slightly greater width than the distance between the rails 8 and 8' so as to provide marginal portions 12, 12' extending beyond the rails. 120

The contiguous ends of the plates 9 and 9' at the center of the roadway are provided with the respective openings 13, 13' extending therethrough at a point beyond the rails. For convenience of description, the open- 125 130

- ings through the plate 9 are indicated by the numeral 13 while the corresponding openings at either side of the plate 9' are designated by the numeral 13'. A band or strip 14 originally U-shaped and in the form of a staple is adapted to have the limbs thereof project through the respective openings 13 and 13', the extremities of which after threading through the plates may then be 10 turned over in the manner shown in Fig. 7 so as to effectively anchor the plates 9 and 9' together for the purpose of preventing undue separation thereof. The plates are connected in this manner at the points extending 15 beyond both of the rails 8 and 8'. The connection afforded by the bands 14 is a hinged one, with enough play between the bands and the openings to provide sufficient movement 20 between the parts to enable both plates to function in the desired manner irrespective of the functioning of the other while at the same time effectively preventing bodily movement of the plates towards the sides of the roadway.
- 25 In order to guard against undue movement of the contiguous ends of the plates 9 and 9' longitudinally of the roadway, a plurality of depending fingers 15 are provided. Preferably two such fingers are provided for each of the plates, one of which is spaced a slight distance from the rail 8 and the remaining finger a corresponding distance from the rail 8'. These fingers may merely consist of pins rigidly held within 30 openings in the plates, with the upper ends of the pins lying flush with the upper surfaces of the plates, such as clearly illustrated in Fig. 7.
- 35 In the preferred embodiments of the invention, both the plates 9 and 9', as well as the supports 8 and 8', are made of metal, so as to enhance the intensity of the reverberations produced by the falling of the plates upon their supports after being raised 40 thereabove due to the striking of the plates by the wheels of vehicles passing thereover. However, the use of metal supports is not absolutely necessary, since the employment of suitable metallic metal for the resounding plates alone, if properly constructed, will produce audible signals of considerable intensity.
- 45 In operation, whenever a vehicle approaches the tracks 2, or other equivalent danger zone, from either direction, the wheels of the vehicle must necessarily traverse the resounding plates of the audible signaling apparatus, and in turn the corrugations 4, and the specially formed portion 5, 5' or 6, as the case may be.
- 50 As soon as the wheels of the vehicle strike the marginal extensions 12 or 12', extending beyond the supporting rails, the resounding plate is caused to bodily rock upon one of its supports and consequently be lifted above 55 the remaining support, one of the supporting rails serving as a fulcrum. As soon as the wheel of the vehicle contacting the plate has advanced over the supporting fulcrum thus provided, the plate is forcibly thrown downwardly upon its other supporting rail, thus giving rise to a pronounced audible signal. Likewise, as the wheel still further advances so as to be in a position just about to leave the plate, it is rocked in a similar manner 60 about the opposite rail as a fulcrum with a consequent repetition of the audible signal just described. During the passage of the front wheels of the vehicle, it is apparent that two distinct audible signals will be given, and two additional audible signals will likewise occur during passage of the rear wheels. During the rocking of the resounding plates in the manner set forth, the tongues 10 and 10' prevent undue lifting 65 movement of the sides of the plate, in a manner which will be apparent from an inspection of Fig. 4 of the drawings, and the depending heads or fingers 15 will function to maintain the contiguous ends of the two 70 plates 9 and 9' in proper operative position with respect to the supporting rails, and the bands 14 to prevent separation of the plates.
- 75 Assuming a vehicle to be approaching the crossing 2, upon traversing the signaling apparatus 3, a distinct audible signal will therefore be first received. This will be followed by a distinctive vibration of the vehicle due to the passage over the corrugations 4, and immediately following this 80 warning, the driver will be confronted with the visible signal provided by the special configuration in the road-bed ahead which will cause him to considerably slacken his speed if traveling at a high rate. It is 85 therefore obvious that the driver will be warned through the faculties of hearing, of feeling, and of sight, all automatically without any special effort on his part, thus effectively and repeatedly informing him of 90 the dangerous crossing ahead. It is obvious that the invention will thus effectively serve to give a positive warning to drivers irrespective of their lack of hearing or of sight. Due to the special construction of 95 the portions of the apparatus for giving the signals, which affect the different faculties of the driver, each of the signals given is distinctive in character, and when the significance thereof has been once understood, will effectively prevent the approach 100 of vehicles to dangerous zones without adequate warning.
- 105 In Fig. 8 of the drawings has been illustrated an alternative method of loosely but 110 permanently anchoring the resounding plates to the supporting rails, adjacent the sides of the roadway. In other words, a method of attaching the plates by a 115 convenient substitute for the struck up tongues 120
- 125
- 130

10 and 10'. In this form, the projecting extremity 11 of the supporting rail is provided with an opening 20 extending therethrough. A bolt 21 is projected through a 5 suitable aperture in the plate and through the opening 20 with the head 21' of the bolt resting upon the upper surface of the plate and the nut 21'' positioned a substantial distance below the extension 11. In 10 order to provide for the necessary relative movement between the plate and the remaining parts, the diameter of the body of the bolt is considerably less than the opening 20 so that the plates may freely 15 rock upon their supports in the manner previously described.

In Figs. 9 to 12 is illustrated another embodiment of means for conveniently supporting the resounding plates. In this embodiment, the supports for the plates preferably comprise a pair of spaced supporting rails 30 and 30' embedded directly in the road-bed flush with the upper surface thereof, with an interposed casting with a central 25 raised portion connected thereto, and upon which the plates directly rest. The casting provided at the center of the roadway is illustrated in plan in Fig. 9, and in transverse section in Fig. 11, being connected at 30 its opposite ends to the rails 30 and 30' as by the bolts 31 and 31', respectively. The casting consists of a web portion 32, an upper flanged portion 33 extending in opposite directions from the web 32, and a flanged 35 base portion 34, likewise extending in opposite directions from the web. The upper flanged portion 33 is convex and at its highest point which extends slightly above the level of the road-bed is provided with 40 elongated slots through which an elongated extremity of a fastening device, such as shown in Fig. 12 of the drawing, may be projected.

The castings employed at the extremities 45 of the plates adjacent the opposite sides of the roadway are similar in every respect to the one just described with the exception that the top and base flanges extend from the web portion in but a single direction. 50 The construction thereof is readily apparent from Fig. 9 of the drawings, the castings at the ends of the plates 9 and 9' being indicated at 35 and 35', respectively.

The resounding plates in this embodiment 55 need not extend laterally beyond the rails 30 and 30', but may terminate coincident therewith in the manner illustrated in Fig. 11.

The opposite ends of each plate are loosely 60 but permanently mounted upon and anchored to the supports provided by the central and end castings in a similar manner and it will therefore be necessary to describe in detail but one of these fastenings. The 65 plate is provided with an elongated opening

36 extending completely therethrough which is substantially rectangular in shape, as will clearly appear from Fig. 9 of the drawings, and corresponding in size and shape to the underlying slots or openings extending 70 through the top flanges of the casting. The opening in the plate is countersunk intermediate its ends at the point indicated at 37 so as to receive therein the head 38 of a specially formed fastening bolt, the body of the 75 bolt 39 being cylindrical in shape, and the lower end thereof being provided with the elongated rectangular portion 40 which is adapted to be passed both through the elongated portion 36 of the opening in the plate 80 and through the elongated openings in the castings. Fig. 12 illustrates the method of cooperation of the head 38 with the countersunk portion of the opening in the resounding plate, and the position which the parts 85 assume when the fastening bolt has been inserted in place and moved into a position to lock the plates to the castings as shown in Fig. 11.

In this embodiment, the resounding plates 90 are merely placed in the relative positions shown in Fig. 9, so as to bring the apertures in the plates into registry with the openings in the underlying supporting castings, the lower end 40 of the fastening bolt is then 95 projected through the elongated portion of the opening in the plate and through the opening in the casting, and subsequently turned so as to bring the portion 40 into the position shown in Fig. 11. The portion 100 100 lies sufficiently below the top flanges of the casting, and the size of the opening through the casting is sufficient to permit free movement of the plate after the parts have been 105 assembled.

The operation of this form will be readily apparent from an inspection of the drawings. The wheels of the vehicle first contact one edge of the resounding plate, rocking it about the fulcrum provided by the raised 110 central portion of the supporting casting thus effectively striking one of the rails, and raising the plate away from the remaining rail. Upon the passage of the vehicle over the fulcrum thus provided the opposite rail 115 is caused to be struck by the plate giving rise to successive audible signals similar to the ones described in connection with the embodiment illustrated in Figs. 3 to 8.

In Figs. 13 to 15 another means for operatively connecting the plates 9 and 9' at their contiguous ends has been illustrated. This means consists of a connecting device T-shaped in cross section, comprising a depending web 40a which is adapted to extend downwardly within the space provided between the plates, and with a head portion 41 adapted to lie immediately upon the upper surface of the plate. The ends of the web 40 are cut away in the manner indicated 120 125 130

at 42 and 42' so as to cooperate with the supporting rails 8 and 8' in the manner clearly indicated in Fig. 14. The opposite extremities of the head 41 extend slightly 5 beyond the sides of the plates and are turned downwardly in the manner indicated at 43 and 43' so as to more effectively maintain the parts in proper position.

The plates are assembled in the manner 10 previously described with the tongues 10 and 10' engaging the extensions of the ends of the rails, the web 40^a is then projected so as to lie between the contiguous ends of the resounding plates, and with the cut away 15 portions engaging the rails as in Fig. 14. The head 41 is then bolted to the projecting marginal portions of the two plates as indicated at 44, 44'. The cooperation of the web 40^a with the rails 8 and 8', effectively preventing 20 undue movement of the plates longitudinally of the roadway as well as separation of the plates while at the same time permitting the necessary movements to permit the production of the audible signals desired. 25

In Fig. 16 has been illustrated a form of the invention particularly adapted for use in connection with narrow highways. In this form, there is but a single plate 30 9^a, which is adapted to rest upon and to be supported by the rails 8, 8' fashioned in all respects similar to those previously described. Each corner of the plate 9^a is provided with a construction corresponding to 35 the corner construction of the plates shown in Fig. 3, with the exception that in the initial fabrication of the plate, the tongues corresponding to 10 and 10' are bent downwardly throughout substantially their entire 40 extent so as to project between the supporting rails when the plate is first placed thereon. After the plates have been placed upon the rails, these tongues may then be forcibly bent so as to partially embrace the reduced 45 extremities of the rails and thus lock the plate loosely but permanently thereto in a manner corresponding identically with that illustrated in Fig. 4 of the drawings.

Instead of forming the central fastening 50 means for locking the plates together in the manner shown in Figs. 13 to 15, the T-shaped member may be formed in the manner shown in Figs. 17 and 18. Fig. 17 shows a sheet metal blank, or a blank formed of other 55 suitable material capable of being folded upon itself in the manner illustrated in Fig. 18. The blank 50 is provided with the apertures 51 at the several points indicated in Fig. 17, and is first bodily bent upon 60 itself along an axis indicated by the line 52, thus forming the web portion 53, shown in Fig. 18, and its side portions 54, 54' are afterwards bent laterally outwards so as to 65 form the head portion of the connecting member. It is to be understood that the

construction formed as in Figs. 17 and 18 is intended merely to replace the connecting member shown in Figs. 13 to 15. The ears 55 and 55' on the blank 51 serve to form portions which project slightly outwardly at 70 the lower ends of the web 53 for engagement below the heads of the supporting rails, similar to the cut away portions 42 and 42' in the form illustrated in Fig. 14.

There is illustrated in Figs. 19 to 21 an 75 embodiment which can be installed with very little expense and without materially disrupting the road-bed at the point of installation. In this form, preferably anchoring portions 60 and 60' made of concrete 80 are provided adjacent the opposite sides of the roadway, and in case the roadway is bordered by raised curbs, parts of the curbs may be broken away to provide spaces for the anchoring portions. The opposite 85 ends of a metallic support 8^a are anchored in portions 60 and 60', as by means of the embedded pins 61 and 61', respectively. The support 8^a is in the form of a flat metal bar which lies directly upon the upper 90 surface of the road-bed and extends the full width thereof. The bar 8^a may also be anchored to the road-bed at a point intermediate its ends as at 61'', if desired.

A similar supporting bar 8^a' is spaced 95 from the bar 8^a and anchored in like fashion by means of the pins 62, 62' and 62''.

Resting directly upon the supporting bars, and loosely but permanently attached thereto, are metallic resounding plates designated 100 by the reference characters 9^b and 9^{b'}, one being placed at either side of the center of the road way as with the first described embodiments.

Both of the resounding plates are loosely 105 attached to the supporting bars by means of bolts such as shown at 63, one of these bolts being preferably located near each corner of the plates. The heads of the bolts rest upon the upper surface of the plates, the bodies thereof pass loosely through suitable sized apertures in the supporting bars, and the nuts 64 carried at the lower ends 110 of the bolts are spaced somewhat below the bars so as to permit the necessary free movement of the plates to assure their intended operation. The nuts may be held 115 against removal by cotter pins or equivalent devices if desired.

In order to permit unobstructed movement 120 of the bolts and nuts after installation of the plates, the portions of the road-bed immediately adjacent and underlying the bolts are removed as indicated at 65 in Fig. 21 to provide recesses receiving them. 125

As in several of the preceding forms, the marginal edges 66, 66' of the plates extend somewhat beyond the supports, and are preferably bent slightly downwards as illustrated in Fig. 21 so as to be more readily 130

traversed by the wheels of the passing vehicle.

This form of the invention is preferably installed by first assembling the resounding plates and their supporting bars. These parts as a unit are then placed in operative position as indicated in the drawings, the recesses 65 having been previously made in the road-bed to receive the lower ends 10 of the bolts and the nuts 64. The concrete anchoring portions may then be made with the extremities of the supporting bars embedded in place. This method of installation is very simple, inexpensive and practical, leaving all of the parts securely fastened in operative position.

The operation of this embodiment will be obvious from the previous description. As the wheels of the vehicle ride either upwardly on one margin towards the center of the plate or downwardly over the other margin in leaving the plate, the same will be rocked bodily about the supporting bars as fulcrums resulting in the production of audible signals due to the falling of the resounding plates upon their supports, similarly to the functioning of the previously described forms of the invention. Although the plates are mounted sufficiently 30 loosely to permit the necessary free movement thereof required, the bolts both limit the degree of rocking movement and prevent displacement of the plates from their supports, and as clearly shown in the drawings the margins 66, 66' are positioned a suitable distance above the surface of the road-bed to permit movement of the plate within the limits defined by the spacing of the nuts 64 below the supporting bars.

40 In accordance with the provisions of the patent statutes, applicant has illustrated and described the preferred embodiment of the invention. It is obvious, however, that various changes in structural details as well 45 as in the arrangement of parts may be made without departing from the spirit of the invention, and it is therefore not intended to limit the invention beyond that particularly defined by the appended claims.

50 I claim:

1. A signaling apparatus for warning drivers upon approaching danger zones of a highway, comprising a support, a resounding plate loosely but permanently mounted 55 upon said support for relative movement

thereto, said plate being disposed so as to be necessarily traversed by a vehicle passing over the road bed.

2. A signaling apparatus for warning drivers upon approaching danger zones of a highway, comprising a support, a resounding plate loosely but permanently mounted on said support and capable of relative movement with respect to the support, said plate being disposed so as to normally lie slightly above the level of the road bed and directly in the path of travel of a vehicle using the highway and adapted to be traversed by the wheels of vehicles passing thereover.

3. A signaling apparatus for warning drivers upon approaching danger zones of a highway, comprising a support, a metallic resounding plate loosely but permanently fixed to said support and capable of rocking movement with respect to the support, said plate being positioned directly in the path of travel of vehicles using the highway so as to be necessarily traversed thereby, the striking of the plate by the wheels of a passing vehicle producing rocking movement of the plate whereby to set up audible reverberations.

4. A signaling apparatus for warning drivers upon approaching danger zones of a highway, comprising a support, a metallic resounding plate loosely but permanently fixed to said support and capable of rocking movement with respect to the support, said plate being disposed directly in the path of travel of vehicles using the highway, and normally positioned slightly above the level of the road bed whereby the passage of the wheels of a vehicle over the plate will set up rocking movement thereof and produce a distinctive audible signal.

5. A device for warning vehicle drivers of approach to a danger zone, comprising a support located in the roadway and extending transversely thereof, and a plate mounted on said support in a manner to be rocked when a vehicle passes over the same and so arranged relative to the support as to strike the latter when rocked and thereby produce an audible sound.

In testimony whereof, I sign my name.

WILLIAM T. MAXWELL.

Witness:

EDWIN O. JOHNS.
